UNITED STATES PATENT OFFICE.

WILLIAM I. BODINE AND CHARLES R. SOLOMON, OF SPRINGFIELD, MISSOURI, ASSIGNEES TO UNITED IRON WORKS COMPANY, OF SPRINGFIELD, MISSOURI, A CORPORATION OF MISSOURI.

REFRIGERATING-MACHINE.

1,198,002.

Specification of Letters Patent. Patented Sept. 12, 1916.

Application filed June 22, 1914. Serial No. 846,708.

To all whom it may concern:

Be it known that we, WILLIAM I. BODINE and CHARLES R. SOLOMON, citizens of the United States, residing in the city of Springfield, county of Greene, and State of Missouri, have invented a certain new and useful Improvement in Refrigerating-Machines, of which the following is a full, clear, and exact description, such as will enable others skilled in the art to which it appertains to make and use the same.

This invention relates to refrigerating machines, and particularly to the compressor and condenser that form part of such machines.

One object of our invention is to provide a compact, self-contained refrigerating machine in which the compressor and condenser are combined as a single unit, thus producing a small, compact machine that is practicable for household use.

Another object is to provide a self-contained refrigerating machine in which the condenser forms a permanent part of the base on which the compressor is mounted, the condensing chamber being formed by a drum-shaped member arranged inside of the base and spaced away from the walls of same so as to form a water-jacket that surrounds the condensing chamber.

Another object is to provide a machine of the character described in which the condensing chamber also serves as a receiver for the condensed liquid.

Another object is to provide a serviceable refrigerating machine of simple construction that comprises few parts and which can be manufactured at a low cost.

Other objects and desirable features of our invention will be hereinafter pointed out.

Briefly described, our improved machine consists of a hollow base, a compressor mounted on said base and provided with a piston which controls the admission of gas through one or more ports formed in the side wall of the cylinder, and a drum-shaped member arranged inside of the base to form a condensing chamber and spaced away from the base so as to form a water-jacket for the condensing chamber, the compressor, of course, being provided with a discharge valve that opens automatically so as to permit the compressed gas to flow from the

cylinder of the compressor into the condensing chamber wherein it is condensed or converted into a liquid state.

Figure 1 of the drawings is a front elevational view of a refrigerating machine constructed in accordance with our invention. Fig. 2 is a vertical longitudinal sectional view of said machine. Fig. 3 is a vertical transverse sectional view taken on the line 3—3 of Fig. 2. Fig. 4 is a horizontal sectional view taken on the line 4—4 of Fig. 2; and Fig. 5 is a vertical transverse sectional view of the condenser taken on the line 5—5 of Fig. 2, looking in the direction indicated by the arrow.

Referring to the drawings which illustrate the preferred form of our invention, A designates the base of the machine which is a hollow member of any preferred cross-sectional shape and provided with legs or feet so as to enable it to be securely connected to a foundation, not shown. A compressor B is mounted on the base A in an upright position, and a hollow drum-shaped member C is arranged inside of the base A and spaced away from the walls thereof, as shown in Figs. 2 and 3, so as to form a condensing chamber.

Instead of equipping the piston 2 of the compressor with a suction valve, we have designed the compressor B in such a manner that the piston of same controls the admission of the gas to the cylinder 3 of the compressor, thereby reducing the cost of manufacturing the compressor and making it practicable to build the compressor in small sizes, owing to the elimination of a suction valve in the piston. As shown in Figs. 2, 3 and 4, one or more inlet ports 4 are formed in the side wall of the cylinder 3 of the compressor at such a point that they will be uncovered when the piston 2 is at the lower end of its stroke, and thus permit the gas to flow into the cylinder from a suction chamber 5 to which a supply pipe 6 leads, said suction chamber being preferably formed in an integral portion 5^a on the side of the cylinder 3. A discharge valve 7 is arranged at the upper end of the cylinder 3, which valve is normally held seated by means of a spring 8 that is interposed between the valve and the head 9 of the cylinder 3. The crank case of the compressor is preferably provided with removable heads

10, one of which is equipped with a stuffing-box, through which the crank shaft 11 of the compressor passes, said shaft also being partly supported by a bearing 12 on the base A of the machine. When the piston 2 moves downwardly on its return stroke, the partial vacuum that is created in the cylinder 3 above the top of the piston, causes the gas to rush into the cylinder through the ports 4 as soon as the piston uncovers said ports. On the succeeding compression stroke of the piston this charge of gas is compressed and forced out of the cylinder when the automatically-operating discharge valve 7 opens, the gas escaping through a pipe or duct 13, shown in Fig. 2, that leads into the condensing chamber C wherein said gas is condensed and converted into a liquid state. The condensed liquid collects in the bottom of the condensing chamber C so that said chamber also acts as a receiver or holder for the liquid. The liquid is conducted away from the condensing chamber C by means of a pipe 14 that leads to an expansion valve, not shown.

In the preferred form of our invention as herein shown, the condensing chamber is formed by a cylindrical-shaped or drum-shaped member of steel, wrought-iron, or other suitable material, that is provided at one end with an integral head 15, the other end of said member being screwed into a head or cap-piece 16 that is detachably connected to the base A of the machine by means of bolts or other suitable fastening devices 17, as shown in Fig. 1. The pipe 13, through which the gas is conducted to the condensing chamber, is screwed into an opening 18 in the removable head 16 of the condenser, and the outlet-pipe 14, through which the condensed liquid is conducted away from the condenser, is also screwed into said removable head. A liquid gage 19 is connected to the removable head 16 of the condenser so as to show the level of the liquid in the condenser, and a high pressure gage 20 is also mounted on said head 16, as shown in Figs. 2 and 5, to indicate the pressure in the condenser.

50. The space between the member C and the walls of the base A forms a water-jacket through which water is supplied by a pipe 21 that is tapped into the base, as shown in Figs. 3 and 4, and the pipe 22 that is tapped into the upper side of the base A, serves to connect the water-jacket of the condensing chamber with a water-jacket at the upper end of the cylinder 3 of the compressor which is preferably formed by means of a shell 23 that is connected to the cylinder by means of a stud 24 and nut 25, as shown in Fig. 2. An oil-drain valve 26 is preferably arranged at the bottom of the condensing chamber C, said valve being mounted in a valve casing 27 on the removable head 16

of the condenser in such a position that it will control the escape of the oil through a drain-pipe 28.

By combining the compressor and the condenser so that they form a single unit, we obtain a small self-contained refrigerating machine that is particularly adapted for household use, the condensing chamber being completely incased by the base of the machine, and coöperating with said base to form a water-jacket that surrounds the condensing chamber. The machine can be made in very small sizes, owing to the elimination of the suction valve, and as the entire machine comprises comparatively few parts which are of simple construction, the machine can be manufactured at a low cost, and is not apt to get out of order when in use.

In addition to the desirable features above mentioned, a machine of the construction above described insures rapid condensation of the gas, owing to the fact that the gas that enters the condenser comes in contact with the surface of a comparatively large body of liquid in the lower part of the condensing chamber, the condensing chamber serving as a holder or receiver for the condensed liquid.

Having thus described our invention, what we claim is:

1. A self-contained refrigerating machine consisting of a compressor and a combined condensing chamber and receiver formed by a hollow base and an approximately tubular-shaped member arranged inside of the base and spaced away from the walls of same.

2. A refrigerating machine, comprising a compressor, a hollow base on which said compressor is mounted, and a condensing chamber carried by and forming a permanent part of said base and consisting of a hollow shell arranged inside of the base and spaced slightly away from the walls thereof.

3. A refrigerating machine, comprising a hollow base, a compressor mounted on said base, and a horizontally disposed, tubular shaped shell arranged inside of said base that constitutes a condensing chamber, said shell being spaced away from the walls of the base so as to form a water-jacket for the condensing chamber.

4. A refrigerating machine, comprising a hollow base, a tubular-shaped shell arranged horizontally inside of said base and spaced away from the walls thereof so as to form a water-jacket that surrounds the condensing chamber, and means for conducting the compressed gas from the cylinder of the compressor to the condensing chamber in said base.

5. A refrigerating machine consisting of a compressor and a water-jacketed condensing chamber combined as a single unit and comprising means for conducting the gas from

the cylinder of the compressor into said condensing chamber, said condensing chamber being formed by two hollow members arranged one within the other and spaced 5 slightly apart.

6. A refrigerating machine consisting of a hollow base, a compressor mounted on said base, a drum inside of said base that constitutes a condensing chamber, said drum 10 being spaced away from the walls of said base so as to form a water-jacket around the condensing chamber, a conduit leading from the discharge port of the compressor to said condensing chamber, and a gage 15 for indicating the level of the liquid in the condensing chamber.

7. A refrigerating machine, comprising a compressor whose cylinder is equipped with a water-jacket, a water-jacketed condensing chamber combined with said compressor as a single unit and consisting of a substantially tubular-shaped member, in the lower portion of which the condensed liquid collects, a connection between the cylinder 20 of the compressor and said condensing chamber, and a connection between the water-jacket of the condensing chamber and the water-jacket of the compressor.

8. A refrigerating machine consisting of a hollow base, a compressor mounted on said base, a tubular-shaped member arranged inside of said base to form a condensing chamber and provided at one end with a head that is detachably connected to the 30 base, and a conduit leading from the discharge port of the compressor to an inlet opening in said head.

9. A refrigerating machine consisting of a hollow base, a compressor mounted on said base, a tubular-shaped member arranged inside of said base to form a condensing chamber and provided at one end with a head that is detachably connected to the base, a conduit leading from the discharge 45 port of the compressor to an inlet opening in said head, and a gage on said head for indicating the level of the condensed liquid in said condenser.

10. A refrigerating machine consisting of a hollow base, a compressor mounted on said base, a tubular-shaped member arranged inside of said base to form a condensing chamber and provided at one end with a head that is detachably connected to the 50 base, a conduit leading from the discharge port of the compressor to an inlet opening in said head, a pressure-gage and a liquid-gage carried by said head, and an

oil-drain valve connected to the lower part of said head.

11. A refrigerating machine, comprising a water-jacketed condensing chamber formed by a drum that is arranged inside of an inclosing shell, a compressor carried by said condensing chamber and permanently combined with same, means for conducting the compressed gases from the cylinder of the compressor into said condensing chamber, and an outlet from said condensing chamber for the condensed liquid.

12. A refrigerating machine consisting of a hollow base, a condensing chamber connected to and forming a permanent part of said base and formed by a hollow member arranged inside of the base and spaced away from same so as to form a space for a cooling medium, a compressor mounted on said base, and a connection between the cylinder of the compressor and the interior of said condensing chamber.

13. A refrigerating machine consisting of a hollow base, a condensing chamber connected to and forming a permanent part of said base and formed by a substantially tubular-shaped member arranged inside of said base and spaced away from same so as to form a space for a cooling medium, a compressor mounted on said base, a conduit for conducting the compressed gas from the compressor into said condensing chamber, and means for supplying a cooling medium to the space between said base and condensing chamber.

14. A self-contained refrigerating machine, consisting of a hollow base provided with means for securing it to a foundation, a tubular-shaped member arranged inside of said base and spaced away from the walls of same, said member being provided at one end with an integral head or end portion, 95 a head at the opposite end of said member that is detachably connected to said base, a compressor mounted on said base, means for conducting the compressed gas from the cylinder of the compressor into said condensing chamber, and means for conducting the condensed liquid out of said condensing chamber.

In testimony whereof, we hereunto affix our signatures in the presence of two witnesses, this 15th day of June, 1914.
